COMBINATION STORAGE AND DISPLAY RACK OR THE LIKE

Kenneth William Baxter, Los Angeles, Calif.
(920 Airway, Glendale, Calif. 91201)

Filed Aug. 1, 1966, Ser. No. 3,278

Term of patent 14 years

(Cl. D80—10)

FIGURE 1 is a front perspective view of a combination storage and display rack or the like embodying my new design;

FIGURE 2 is a front perspective view of a modified form of the combination storage and display rack or the like shown in FIGURE 1;

FIGURE 3 is a front elevational view of the rack shown in FIGURE 1;

FIGURE 4 is a side elevational view of the rack shown in FIGURE 1;

FIGURE 5 is a top plan view of the rack shown in FIGURE 1; and

FIGURE 6 is a cross-sectional view taken on line 6-6 of FIGURE 3.

The dominant features of my design reside in the portions shown in full lines, the casters being omitted from FIGURES 5 and 6 for convenience of illustration.

I claim:
The ornamental design for combination storage and display rack or the like, as shown and described.
